DRY ICE MACHINE

Charles L. Hill, Plainfield, N. J.

Application December 17, 1936, Serial No. 116,287

10 Claims. (Cl. 62—121)

This invention relates to improvements in ice making apparatus and more particularly to a device for making dry ice in cake form.

One of the main features of the invention is 5 to provide a freezer device by which dry ice in cake form may be instantly made from carbonic gas as and when needed, which adapts the device for use in laboratories, clinics, metallurgical work and for store keepers in the packaging of ice 10 cream, fruit juices and the like.

Another feature of the invention resides in a 15 small compact dry ice making device which is automatic in its action, small and compact of construction, and which is safe of operation and highly efficient and economical even though operated by one unskilled in the art of dry ice manufacture.

A further feature of the invention is the provision of a dry ice making device which audibly 20 indicates to the user when the cake forming cavity has become filled with dry ice, thus notifying the user that the flow of carbonic gas to the cavity should be shut off.

With these and other objects in view, the invention relates to the novel construction, combination and arrangement of parts, the essential 25 features of which are hereinafter fully described in the following specification, are particularly pointed out in the appended claims, and are illustrated in the accompanying drawing, in which:

Figure 1 is a perspective view of my dry ice 30 making device connected with a tank of carbonic gas, the control valve of the device being shown in "on" position in full lines, and in "off" position in dotted lines.

Figure 2 is an enlarged vertical longitudinal 35 sectional view through the dry ice making device, the control valve being shown in "off" position.

Figure 3 is a horizontal sectional view on the 40 line 3—3 of Figure 2.

Figure 4 is a fragmentary vertical sectional 45 view taken at right angle to Figure 2, but showing a formed cake of dry ice and the cover in partially open position.

Figure 5 is a fragmentary top plan view of the 50 device with parts broken away.

Referring to the drawing by reference characters, the numeral 10 designates my improved dry ice making device in its entirety and which 55 includes a hollow cylindrical base or casing 11 closed at its top by a flat top wall 12 and open at its bottom, the bottom being provided with outwardly extending flanges 13 having screw openings therein for the passage of screws 14 for the purpose of fixedly securing the device to a

supporting structure. The side wall of the base 11 is provided with opposed slots 14 and 15, the said slots extending inwardly from the bottom end of the side wall for a purpose to be presently explained.

Rising upwardly from the top wall 12 inwardly of the periphery thereof is an annular rib 16, the inner side of the rib defining a recess 17, the bottom wall of which is provided with an annular undercut 15 groove 21 for receiving a split clamping ring 22, the said ring serving to hold a porous disk 23 seated within the recess 17 and which disk overlies the concentric grooves 19. The porous disk member 23 comprises an inner layer of finely woven canvas 24 and an outer disk of fine mesh screen 25 so as to provide an impervious but yet porous bottom for the recess 17. The porous disk member 23 is provided with a central opening 26 which registers with the opening 18 in the top 20 wall 12 and passing through these registering openings is an externally screw threaded jet member 27. Clamping nuts 28 are threaded upon the jet member 27 to secure the same to the top wall 12, while the lower end of the jet member 30 extends downwardly into the hollow base 11, the said lower end being provided with a flange 29. The jet member 27 is provided with three radially arranged orifices 30, each of which is substantially semi-circular shaped in cross section, and these orifices provide restricted outlet passages 35 for the gaseous refrigerant used in the making of dry ice.

Suspended from the jet member 27 and concealed within the hollow base 11 is a control 40 valve 31, the same comprising a casing 32 having a horizontally disposed nipple 33 which extends outwardly through the slot 15 and through which nipple passes the inlet 34 of the valve. Threaded to the nipple 33 is a coupling nut 35 which joins one end of a copper tube 36 to the nipple 33, the other end of the tube extending to the outlet 37 of a tank 38 containing the gaseous refrigerant, and which gas is generally carbon-dioxide (CO₂). Rising upwardly from the body 32 of the valve is 45 an outlet nipple 39 and threaded thereto is a coupling nut 40 which connects the lower end of the jet member 27 with the outlet passage 41 of the valve. Extending from the valve casing 32 diametrically opposite the inlet nipple 33, is 50 55

an internally screw threaded nipple 42 to which a bushing nut 43 is threaded, the said bushing nut acting as a bearing for the stem 44 of a conical valve element 45, the said element coacting with a seat 46 at the juncture of the passages 34 and 41 for the purpose of opening and shutting off the supply of refrigerant from the tank 38 to the jet 27. The valve element 45 is threaded as at 47 to the valve casing, and the outer end 10 extends through the slot 14 and has secured thereto an actuating handle 48, the said handle being disposed beyond the outer side wall of the base 11. It will be seen that by turning the handle 48 to the vertical position shown in Figure 1, 15 the valve may be opened or by turning the same to the dotted position shown in Figure 1 or the position shown in Figure 2, the supply of refrigerant through the valve will be shut off.

Pivotedly connected as at 49 to the top of the 20 cylindrical base 11 is a cover member 50, the same having a cavity or recess 51 in the under side thereof. Set into the under side of the cover 25 50 is a rubber gasket 52 which engages the rib 16 when the cover member is swung down to a closed position over the top of the base 11. For the purpose of securing the cover member in a tight sealed closed position, there is provided a hand lever 53, the same being pivoted to the cover as at 54, the hand lever adjacent the pivoted 30 end being provided with a hook 55 which is adapted to engage a pin 56 carried by spaced ears 57 which extend from the side wall of the cylindrical base 11. When the cover member 50 is swung to closed position and the hook portion 55 of the lever 53 is engaged with the pin 56, the cover 50 is sealed with respect to the top of the base 11, and the cavity 51 is ready to receive the refrigerant from the outlet end of the orifices 30 in the jet member 27.

40 Carried by the cover 50 centrally thereof, is an audible safety blow off valve 58, the same including a cylindrical body member 59 having at its lower end, an enlarged externally screw threaded head 60, and extending from the head 45 60 is a reduced threaded nipple 61 which threads into the top of the cover member 50. A passage 62 extends through the head 61 and establishes communication between the cavity 51 and the sleeve body 59. Threaded to the head 60 is the 50 lower end of a cylindrical cap 63, the walls of the cap being disposed in spaced relation with respect to the sleeve body 59. Normally seated against the inner end of the passage 62, is the rounded head 64 of a valve member 65, the said 55 valve member having a socket 66 within which a spring 67 extends, one end of the spring engaging the end wall of the socket whereas the opposite end of the spring abuts the upper end wall of the cap 63. The spring 67 is of such pre-determined tension as to maintain the valve head 64 seated until such time as an excessive pressure 60 occurs in the cavity 51 after the formation of a cake of dry ice therein, after which the spring 67 yields under the excess pressure within the cavity, causing the valve head 64 to open and enabling the refrigerant to pass through the sleeve body 59 into the space between the sleeve body and the cap 63, after which the refrigerant passes to the atmosphere through openings 68 provided in the head 60.

In practice, the cover 50 is held locked down against the top of the base 11 by engaging the hook portion 55 of the hand lever 53 with the pin 56. The handle 48 of the valve 31 is turned 70 to the "up" position shown in full lines in Figure

1 causing the valve 31 to open, thus admitting carbon dioxide from the tank 38 to the cavity 51 through the restricted orifices 30 of the jet member 27. Due to the sudden expansion of the carbon dioxide (CO₂) within the cavity 51, it follows that the cavity will become substantially filled with dry ice due to the solidification of the carbon dioxide to produce a cake of dry ice substantially of the shape shown at 69 in Figure 4, the waste gases of the refrigerant being permitted 10 to pass through the porous disk 23, grooves 19, openings 20 into the hollow base 11 and thence outwardly through the slots 14 and 15. After the filling of the cavity 51 by the formation 15 of dry ice therein, which requires but a few seconds, the pressure within the cavity is relieved by the audible safety blow off valve 58, the fluid refrigerant passing from the jet member 27, through the porous cake of dry ice 69 to the cavity 51 and thence through the safety valve 58, and 20 due to the restricted outlet openings 68, a hissing sound will be produced and which constitutes an audible signal to an operator that the valve 31 should be shut off by moving the handle 48 to the "down" position shown in Figure 2. After 25 the control valve 31 has been shut off, the hand lever 53 is actuated to unlock the cover 50, after which the cover is swung to raised position as shown in Figure 4 and the cake of dry ice 69 is free to be lifted from the top of the base 11. 30

While I have shown and described what I consider to be the most practical embodiment of my invention, I wish it to be understood that such changes and alterations as come within the scope of the appended claims may be resorted to if 35 desired.

Having thus described the invention, what I claim as new and desire to secure by Letters Patent of the United States, is:—

1. In an apparatus of the class described, 40 means providing an ice forming cavity, means for introducing a fluid refrigerant under pressure into said cavity, valve means for controlling the flow of refrigerant to said cavity, and a pressure relief valve through which excess fluid pressure passes 45 for releasing the fluid pressure from within said cavity after the formation of a cake of solidified refrigerant therein.

2. In an apparatus of the class described, means providing an ice forming cavity, means for introducing a fluid refrigerant under pressure into said cavity, manual control means for regulating the flow of refrigerant to said cavity, pressure actuated means for relieving the cavity of excess fluid pressure after the formation of a cake 55 of solidified refrigerant therein, and audible signal means operable by the fluid pressure released by said pressure actuated means for audibly indicating the releasing of excess fluid pressure from said cavity. 60

3. In an apparatus of the class described, a base member, a cover member having a recess which coacts with said base member to provide an ice forming cavity, means for releasably securing said cover in sealed closed position against 65 said base member, means for introducing a fluid refrigerant under pressure to said cavity, and pressure relief valve means on said cover member for relieving the cavity of excess fluid pressure after the formation of a cake of solidified 70 refrigerant therein.

4. In an apparatus of the class described, a base member, a cover member having a recess therein which coacts with said base member to provide an ice forming cavity, means for releas- 75

ably securing said cover member in sealed closed position against said base member, means for introducing a fluid refrigerant under pressure to said cavity for solidification therein, and pressure relief means for audibly indicating when the cavity becomes filled with the solidified refrigerant.

5. A dry ice making device comprising in combination, a hollow base having a recess in 10 the top wall thereof, the interior of said hollow base opening to the atmosphere through openings provided in the side walls thereof, a flat porous member seated in said recess, the bottom wall of said recess having gas releasing openings therein, 15 a cover member having a recess therein and cooperating with the top wall of said base to provide a dry ice forming cavity, means for releasably securing said cover member in sealed closed position against the top wall of said base, and 20 means for introducing a fluid refrigerant under pressure into said cavity through the top wall of said base and centrally through said flat porous member.

6. A dry ice making device comprising in combination, a hollow cylindrical base having a top 25 wall and an opening in the side wall thereof, an annular upstanding rib rising upwardly from said top wall and defining a recess, spaced concentric grooves provided in the bottom wall of 30 said recess communicating with the inside of said cylindrical base through small openings provided in said top wall, a flat porous disk seated in said recess, a cover member having a cavity therein, means for releasably securing said cover member 35 in sealed engagement with said rib, and means for introducing a gaseous refrigerant under pressure into the cavity through the top wall of said cylindrical base and centrally through said flat porous disk whereby waste gases of the gaseous 40 refrigerant during the formation of a cake of dry ice in said cavity may be released through said porous disk to the atmosphere.

7. A dry ice making device comprising in combination a hollow cylindrical base having a top 45 wall and an opening in the side wall thereof, an annular upstanding rib rising upwardly from said top wall and defining a recess, spaced concentric grooves provided in the bottom wall of 50 said recess communicating with the inside of said cylindrical base through small openings provided in said top wall, a flat porous disk seated in said recess, a cover member having a cavity therein, means for releasably securing said cover member 55 in sealed engagement with said rib, means for introducing a gaseous refrigerant under pressure into the cavity through the top wall of said cylindrical base and centrally through said flat porous disk whereby waste

gases of the gaseous refrigerant during the formation of a cake of dry ice in said cavity may be released through said porous disk to the atmosphere, and a pressure relief valve mounted on said cover member for releasing the pressure of 5 the fluid refrigerant from within said cavity when the same becomes filled with dry ice.

8. A dry ice making device comprising in combination, a hollow cylindrical base having a top wall and an opening in the side wall thereof, a 10 cover member having a recess therein which cooperates with said top wall to provide a dry ice forming cavity, means for releasably securing said cover member in sealed closed position against the top wall of said base, a jet extending 15 centrally into said cavity through the top wall of said base, means connected with said jet for supplying a gaseous refrigerant under pressure to said cavity, means in the top wall of said base for the escape of the waste gases from said cavity to 20 the inside of said hollow base during the solidification of the refrigerant in said cavity to form dry ice, and means on said cover member for releasing the excess pressure of refrigerant from 25 within said cavity when the latter becomes filled with dry ice.

9. A dry ice making device comprising in combination, a hollow cylindrical base having a top 30 wall and opposed slots in the side wall extending inwardly from the bottom thereof, a manual control valve concealed within said hollow cylindrical base and provided with an actuating handle projecting outwardly through one of said slots and a pipe coupling at the inlet side of said valve 35 extending through the other of said slots and adapted to be connected with a gaseous refrigerant supply, a jet member extending centrally through the top wall of said base and secured thereto, said jet member being connected with the outlet side of said valve, a cover member 40 having a recess therein and cooperating with the top wall of said base to provide a dry ice forming cavity, and means for releasing waste gases from said cavity to the atmosphere through said hollow base during the solidification of the refrigerant 45 within said cavity.

10. In a dry ice making device, a pair of members held in sealed clamped relation and coacting to provide an ice forming cavity, means for introducing a gaseous fluid refrigerant under pressure 50 into said cavity, and a safety audible relief valve mounted in one of said members for the direct release of the excess refrigerant therethrough from said cavity to the atmosphere when the fluid pressure therein rises to a predetermined 55 degree by reason of the cavity becoming filled with solidified refrigerant.

CHARLES L. HILL.
